United States Patent Office

Des. 186,172

Patented Sept. 22, 1959

186,172

TELEVISION REMOTE CONTROL OR SIMILAR ARTICLE

Cyrilla A. Seymour, Chicago, Ill., assignor to Admiral Corporation, Chicago, Ill., a corporation of Delaware

Application December 12, 1958, Serial No. 53,753

Term of patent 3½ years

(Cl. D26—13)

Fig. 1.

Fig. 2.

Fig. 3.

Fig. 4.

Fig. 5.

Fig. 1 is a top plan view of a television remote control or similar article, showing my new design;

Fig. 2 is an elevational end view thereof as observed from the left of Fig. 1;

Fig. 3 is a side elevational view, a portion thereof being broken away;

Fig. 4 is also an elevational end view as observed from the right of Fig. 1; and

Fig. 5 is a bottom plan view of the television remote control.

I claim:

The ornamental design for a television remote control or similar article, as shown and described.
